UNITED STATES PATENT OFFICE.

CHARLES F. FERNALD, OF LOS ANGELES, CALIFORNIA, ASSIGNOR OF ONE-HALF TO
JAMES W. SWARTZLANDER, OF LOS ANGELES, CALIFORNIA.

SAND REEL.

Application filed February 6, 1925. Serial No. 7,300.

This invention relates to improvements in bearings and shifting devices for shifting or swinging a sand reel shaft upon a well drilling derrick.

5 It is an object of this invention to provide an improved bearing and means for shifting the bearing so that the sand reel shaft may be shifted, causing the friction pulley mounted thereon to engage the band wheel 10 upon the derrick.

With the foregoing and other objects in view which will be made manifest in the following detailed description and pointed out in the appended claim, reference is had 15 to the accompanying drawings for an illustrative embodiment of the invention, where- in:

Figure 1 is a side elevation showing a portion of a well drilling derrick upon 20 which is mounted the sand reel shaft and the band wheel;

Fig. 2 is a rear elevation of the derrick and may be considered as taken substantially on the line 2—2 of Fig. 1;

25 Fig. 3 is a vertical section through the bearing which supports and shifts the sand reel shaft, and may be considered as taken upon the line 3—3 of Fig. 4;

Fig. 4 is a vertical section taken upon the 30 line 4—4 of Fig. 3;

Fig. 5 is a side elevation of the bearing shown in Figs. 3 and 4 with the actuating lever secured thereto;

Fig. 6 is a view in elevation taken in the 35 direction of the arrow 6 upon Fig. 5;

Fig. 7 is a top plan view of the box in which the sand reel shaft shifting bearing is disposed; and

Fig. 8 is a top plan view of the box in 40 which the shifting bearing for the sand reel shaft is disposed, the cap for the box being shown as having been removed.

Referring to the accompanying drawings wherein similar reference characters designate similar parts throughout, the derrick is shown as being provided with mud sills 45 10, upon which rest the sand reel sill 11 and the subsill 12. The sand reel posts 13 are shown as mounted upon the sand reel sill 11 and upon the subsill 12. Upon the conventional derrick there are also provided

jack posts 14, which support the band wheel shaft 15 carrying the band wheel 16. The tug pulley for the bull rope is shown at 17 and the tug pulley for the calf wheel rope 55 is shown at 18. The band wheel shaft 15 is also provided with a crank 19, upon which may be secured the pitman rod for the walking beam. The sand reel shaft 20 is supported upon the sand reel posts 13 60 and has mounted thereon the sand reel 21 and the friction pulley 22. In order to drive or rotate the sand reel 21, it is customary to swing one end of the sand reel shaft 20 so as to bring the friction pulley 22 into 65 engagement with the periphery of the band wheel.

Heretofore it has been customary to provide a lever pivoted upon the subsill 12 or adjacent the bottom of the sand reel post 13 and to mount a bearing upon the lever, so that when the lever is pulled by the sand 70 reel reach, indicated at 23, the sand reel shaft would be swung to bring the friction pulley 22 into engagement with the band wheel. This construction required a considerable force to be applied upon the sand reel reach 23 in order to keep the friction pulley 22 in good frictional engagement with the band wheel. 75

By the improved construction a lever is provided which is attached to the bearing of the sand reel shaft, which lever has a type of traveling fulcrum, and in this manner the leverage is greatly increased without decreasing the throw or movement of the sand reel shaft 20. Upon the sand reel post 13 which rests upon the subsill 12 there is provided a box 24, which has its bottom portion 25 resting upon the top of the sand reel post 13 and which is provided with upwardly extending side walls 26. Lag screws 27 may be employed which extend through the bottom 25 of the box 24 into the top of the sand reel post 13, so as to prevent shifting of the box upon the post. Upon the top of the box there is placed a cap 28 which is preferably ribbed, as indicated at 28', to strengthen the cap. The sides 80 of the box 24 are provided with recesses 29 capable of partially receiving bolts or tie rods 30 which extend through the subsill 109

12 and are provided at their lower ends with nuts 31. Nuts 32 are provided upon the upper ends of the bolts or tie rods 30 and serve to maintain the cap 28 upon the box 24, and also to maintain the box 24 upon the sand reel post 13. By placing the tie rods 30 within the recesses 29 upon the sides of the box, the tie rods assist the lag screws 27 in preventing shifting of the box upon the sand reel post.

Within the box 24 there is placed a bearing, generally designated at 33, in which the sand reel shaft 20 is rotatable. The bearing 33 is a split bearing consisting of members 34 and 35, the member 34 being uppermost and the member 35 being lowermost within the box 24. Recesses 36 are formed in the upper member 34 and cap screws 37 have their heads disposed within the recesses and serve to secure the members 34 and 35 together about the sand reel shaft 20. The members 34 and 35 may be babbitted, as indicated at 38, and may be separated slightly by suitable shims, indicated at 39. The upper member 34 presents a semi-cylindrical surface having the recesses 36 formed therein, and in this manner the heads of the cap screws 37 do not project from the cylindrical surface provided by the upper member 34. The lower member 35 has gear teeth 40 provided upon its exterior surface, and these gear teeth are adapted to rest upon or mesh with rack teeth 41 formed upon the bottom 25 of the box 24. The cap 28 is separated from the side walls 26 of the box 24 by means of shims 43, preferably of the same thickness as the shims 39, for a purpose hereinafter to be described.

A lever 44 is provided which has an enlarged lower end, indicated at 45. Stud bolts 46 pass through the lower end of the lever 44 and extend into the ends of the members 34 and 35 comprising the split bearing 33. The stud bolts 46, which pass into the upper member 34 of the split bearing, extend through slotted or elongated holes 47 formed in the lever 44 for a purpose hereinafter to be described. A suitable collar 48 is provided which is rigidly secured upon the sand reel shaft 20 by a set screw 49, and this collar bears against the face of the enlarged portion 45 of the lever 44. A pipe section 50 is adapted to be telescoped over the upper end of the lever 44 and is pivotally connected, as at 51, to the end of the sand reel reach 23. A bearing 52 which is provided in the other sand reel post 13 is a slightly loose bearing, so that as the sand reel shaft 20 is shifted, it will not bind upon the end of the sand reel shaft disposed therein.

The operation of the device is as follows: When the sand reel reach 23 is pulled, it swings the lever 44 and in this manner causes rotation of the split bearing 33, in which the sand reel shaft 20 is rotatable. Rotation

of the split bearing 33, because of the engagement between the gear teeth 40 and the rack teeth 41, causes the bearing to roll or move within the box 24 and thus swings the sand reel shaft 20 so as to bring the friction pulley 22 into engagement with the peripheral surface of the band wheel 16. In a similar manner, if the sand reel reach 23 is pushed, the lever 44 will be swung in the opposite direction, causing rotation of the split bearing 33 in the opposite direction, and cause it to roll toward the opposite side of the box 24, thus bringing the friction pulley 22 into engagement with the lagging 33, which is mounted upon the brake post 54, so that the pulley 22 will be caused to stop rotation, and thus brake or stop the sand reel shaft 20. In this manner a type of traveling fulcrum is provided for the lever 44 and the leverage obtained by the lever is much greater than that which would be obtained if the lever 44 were pivoted upon the subsill 12 or adjacent the bottom of the sand reel post 13 mounted thereon.

If the bearing 33 becomes worn, it is possible to remove the shims 39 upon withdrawal of the cap screws 37, bringing the upper member 34 closer to the lower member 35 and thus tightening the bearing about the sand reel shaft 20. When this is done, the stud bolt 46, which extends through the lever 44 into the member 34, slides downwardly within its slot 47, and at the same time the shim 43 is removed so that the cap 28 of the box 24 will be maintained adjacent the top of the upper member 34, it being understood that there is merely a working clearance between the cylindrical surface provided by the upper member 34 and the lower surface of the cap 28, so that up and down vibration of the split bearing 33 within the box 24 is prevented. An oil hole 55 may be provided in the cap 28 and another oil hole 56 may be provided in the upper member 34 of the split bearing 33. The top of the oil hole 56 is preferably flared or countersunk, as indicated at 57, so that regardless of which position the split bearing 33 is in within the box 24, oil fed through the oil hole 55 will pass into the oil hole 56 and lubricate the bearing 33.

From the above it is seen that an improved shifting bearing for the sand reel shaft upon a well drilling derrick is provided, which consists essentially of a bearing, in which the sand reel shaft is rotatable, and means for rotating the bearing so as to cause it to roll within a box, thus shifting the sand reel shaft.

It will be understood that various changes in the detail of construction may be made without departing from the spirit or scope of the invention as defined by the appended claim.

I claim:

A bearing for sand reel shafts comprising a bearing in which the shaft is rotatable, gear teeth formed upon one member of said bearing, a box having teeth provided thereon upon which said gear teeth may rest and 5 mesh, a cap for said box for maintaining the teeth upon said bearing in engagement with

the teeth on said box, and means for rotating said bearing so as to cause it to move within said box and thus shift the shaft. 10

In testimony whereof I have signed my name to this specification.

CHARLES F. FERNALD.
